COMBINED SALT SHAKER AND PEPPER MILL OR SIMILAR ARTICLE

Henry Wish, Tuckahoe, N.Y., assignor to Lucky Wish
Products, Inc., Holbrook, N.Y., a corporation of New York

Filed Apr. 5, 1961, Ser. No. 64,628

Term of patent 7 years

(Cl. D44—22)

FIG. 1 is a top plan view;
FIG. 2 is an elevational view; and
FIG. 3 is a fragmentary elevational view, partly in section, and with the cap removed.

I claim:

The ornamental design for a combined salt shaker and pepper mill or similar article, substantially as shown.
